BIT HOLDER FOR CUTTER CHAIN BITS

Clarence H. Brown, Chicago, Ill., assignor to Goodman Manufacturing Company, Chicago, Ill., a corporation of Illinois

Application November 18, 1957, Serial No. 696,982

1 Claim. (Cl. 262—33)

This invention relates to improvements to cutter chain blocks particularly adapted for continuous mining machines and the like, and more particularly relates to a simplified and improved detachable mounting for the cutter chain bit in its chain block.

A principal object of the present invention is to provide a simplified holding means for a cutter chain bit in its chain block which eliminates the use of the usual set screws for holding the bit to its block.

Another object of the invention is to provide a new and improved cutter chain block having a simplified holding means for holding the cutter chain bit to the block so arranged as to tighten the bit within the block by the cutter forces acting on the bit and to accommodate ready release of the bit from its block.

Another object of the invention is to provide a self-retaining holding connection for a cutter chain bit to its block in which the cutting forces acting on the bit and block serve to tighten the bit to its block and in which the bit may readily be removed from its block by a simple prying action on the holding means therefor.

A still further object of the invention is to provide a self-retaining holding device for holding a cutter bit to its block, in which a strap extends from the block and has an inner face conforming to a face of the cutter bit, and in which a bit holder is slidably movable within said strap and has faces facing the inner face of said strap, for engagement with opposite cutting faces of the bit, and forcing the bit into engagement with the inner face of said strap by the cutting forces acting on said bit.

These and other objects of the invention will appear from time to time as the following specification proceeds and with reference to the accompanying drawings wherein:

Figure 1 is a view in side elevation of a cutter chain block and bit, with the bit holding portion of the block broken away and shown in section in order to show the bit holder structure of the invention;

Figure 2 is a front end view of the cutter chain bit and block shown in Figure 1; and

Figure 3 is a fragmentary sectional view taken substantially along line 3—3 of Figure 1.

In the embodiment of the invention illustrated in the drawing, reference character 10 designates generally a cutter bit carrying cutter chain block. The cutter chain block 10 is one of a plurality of links of a cutter chain used for cutting coal in mines underground and guided for orbital travel in the usual guide or cutter bar indicated by dot and dash lines in Figure 2 and designated by reference character 11.

The cutter chain block 10 is shown as including a lug 12 having spaced link portions 13 formed integrally therewith and extending from opposite sides thereof and having gibs 14 extending along the inner sides thereof, for engagement with the conventional guides in the cutter bar.

The link portions 13 are shown as being drilled at 15 to accommodate the blocks 10 to be connected together in the form of a continuous chain by the usual connect-

2

ing straps or links (not shown) pivotally connected thereto by pivot pins (not shown), as is well known to those skilled in the art, so not herein shown or described further.

5 The lug 12 is herein shown as having parallel spaced side walls 16, spaced inwardly from the outer faces of the link portions 13. The side walls 16 are engaged by the inner faces of parallel spaced legs 17 of a bit retaining strap 19, secured to said lug as by roll pins 20 or a 10 like securing means, which may readily be removed by a punch or the like, to accommodate the removal of said strap from said lugs.

The bit retaining strap 19 has generally a V-shaped closed end portion having inner faces 21 terminating at 15 an apex 23. The faces 21 and apex 23 are inclined outwardly from the rear to the forward end of said strap 19 at the angle of an outer edge 24 of a cutter bit 25 to react against and pitch said cutter bit at the required cutting angle.

20 The cutter bit 25 is of a well known form of cutter bit, commonly known as a throw-away type of cutter bit, diamond shaped in cross-section. Said cutter bit has oppositely inclined faces 26 inclined inwardly from positions adjacent the transverse center of the bit, from the 25 opposite edge of the bit from the edge 24, and forming cutting points at the junctures of said inclined faces with the edge 24, and thus providing a reversible bit of an economical construction, which may be thrown away when worn. The bit 25 is retained in position within 30 the strap 19 by a bit holder jaw 27 slidably mounted on the outer face of the lug 12 within the legs 17 of the strap 19, for slidable movement along said lug and strap.

The bit holder 27 has outer faces 29 and 30 conforming to the angle of inclination of the inclined faces 26 35 of the bit 25 and connected together by a rectilinear face 31 inclined at the angle of the edge 24 of the bit. The face 21 with the oppositely inclined faces 29 and 30 forms a recess for receiving the bit 25 and retaining said bit to the strap 19, by the cutting forces acting on said 40 bit and said bit holder.

As herein shown, the lug 12 has spaced ears 33 and 35 extending outwardly therefrom, forming slidable mountings for a pin 36 extending through spaced ears 37 and 39, extending inwardly from the bit holder 27.

The bit holder 27 is shown as being retained to the 45 pin 36, as by a pin 40 or like retaining device, and is shown as being biased toward the rear of the lug 12 as by a compression spring 41, encircling the pin 36 and interposed between the ear 33 extending from the lug 12 and the ear 39 extending from the bit holder 27.

50 The spring 41 thus biases the bit holder inwardly along the strap 19 and accommodates said bit holder to be moved outwardly of said strap in a forward direction by a pry bar 42. The pry bar 42 has a C-shaped engaging end portion engageable with a recess 43 in the outer face of the strap 19, and with the rear face of the bit holder 27, to force said bit holder in a forward direction with respect to the strap 19 upon the exertion of a prying force on the bar 42 in a direction, which is shown in Figure 1 as being in a clockwise direction.

60 Thus, when it is desired to insert a bit within the bit holder it is merely necessary to force the bit holder 27 outwardly with respect to the strap 19 and to then insert a bit therein into engagement with the inclined faces 29 and 30 and then release the holder and accommodate the spring 41 to bias the bit holder into engagement with the bit and to bias the bit into engagement with the inclined faces 21 of the strap 19.

65 It may be seen from the foregoing that a simplified form of bit holder particularly adapted for bits of the throw-away type has been provided, which does away with the usual set screws and like securing devices and

makes it possible to replace the bit by a simple prying action on the rear face of the bit holder.

It may further be seen that the cutting forces on the bit and bit holder force the bit into engagement with the inclined faces 21 of the strap 19, to retain said bit to said strap by the normal cutting forces acting thereon, and that the harder the cutting forces, the greater will be the retaining pressure of the bit to the strap and lug.

While I have herein shown and described one form in which my invention may be embodied, it should be understood that various modifications and variations of the invention may be effected without departing from the spirit and scope of the novel concepts thereof as defined by the claim appended hereto.

I claim as my invention:

In a cutter block, a cutter bit adapted to be held in place in said block, said bit being generally diamond shaped in cross-section and having oppositely inclined faces inclined from one edge portion of the bit from positions adjacent the transverse center of the bit to opposite ends of an opposite edge portion of the bit and defining cutting points at opposite ends of said opposite edge portion of the bit, said cutter block having a lug extending longitudinally therealong having parallel spaced longitudinally extending side walls and an outer face inclined outwardly from the rear to the forward end of said lug having longitudinally spaced ears extending outwardly therefrom, means for securing said bit to said lug comprising a strap generally U-shaped in cross-section having a closed outer end portion and parallel legs extending therefrom along opposite sides of said lug, means detachably

securing said parallel legs to said lug, the inner wall of the closed outer end portion of said strap having inner bit engaging surfaces inclined outwardly from an apex to conform to the sides of said bit and inclined outwardly from the rear to the forward end of said strap at the cutting angle of said bit, a bit holding jaw slidably guided on the outer inclined face of said lug between the legs of said strap and having oppositely inclined advance and retreating bit engaging faces facing the closed end of said strap and conforming to the oppositely inclined faces of said bit for retaining said bit into engagement with the apex of the inner wall of said strap by the action of the cutting forces on said bit, said jaw having longitudinally spaced ears extending inwardly therefrom in advance of the ears extending outwardly from said lug, a pin extending through said ears extending from said lug and said jaw and slidably guiding said jaw on said lug, and a spring on said pin biasing said ears into engagement with each other and said jaw into retracted relation with respect to said strap, and accommodating release of said bit by pressing on the rear end of said jaw and compressing said spring.
